UNITED STATES PATENT OFFICE

167,661

CIGARETTE LIGHTER

Herman G. Treiss, Jr., Brooklyn, N. Y., assignor
to American Safety Razor Corporation, Brooklyn, N. Y., a corporation of Virginia

Application October 23, 1950, Serial No. 12,660

Term of patent 14 years

(Cl. D48—27)

To all whom it may concern:

Be it known that I, Herman G. Treiss, Jr., a citizen of the United States, and a resident of Brooklyn, county of Kings, and State of New York, have invented a new, original, and ornamental Design for a Cigarette Lighter, of which the following is a specification, reference being had to the accompanying drawings, forming part thereof:

Fig. 1 is a perspective view of a cigarette lighter, showing my new design;

Fig. 2 is a side elevational view thereof;

Fig. 3 is a front elevational view thereof; and

Fig. 4 is a top plan view thereof.

I claim:

The ornamental design for a cigarette lighter, as shown.

HERMAN G. TREISS, JR.
